CLAIM

The ornamental design for a case for receiving magnetic recording mediums, as shown and described.

DESCRIPTION

FIG. 1 is a top perspective view of a case for receiving magnetic recording mediums showing my new design;
FIG. 2 is a front elevation thereof;
FIG. 3 is a left side elevation thereof;
FIG. 4 is a right side elevation thereof;
FIG. 5 is a rear elevation thereof;
FIG. 6 is a top perspective view thereof, in an open position; and,
FIG. 7 is a second embodiment of FIG. 6.
The bottom is identical to the top as shown in FIG. 1.

FIG. 1

FIG. 2

FIG. 3

FIG. 4

FIG. 5

FIG. 6

FIG. 7
